(57) **CLAIM**

The ornamental design for a strap, as shown and described.

DESCRIPTION

FIG. 1 is a perspective view of a strap showing my new design in a closed state;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view thereof, taken from portion '9' in FIG. 2;

FIG. 10 is another perspective view thereof, showing the strap, shown in an open state; and,

FIG. 11 is another perspective view thereof, showing the strap shown in an open state.

The dot-dash dot broken lines of FIGS. 2 and 9 are included to show a partially enlarged view only and form no part of the claimed design.

1 Claim, 11 Drawing Sheets
